220	1221	1222	1223	1224	1225	1226	1227	1228	1229	1230	1231	1232	1233	1234	1235	1236	1237	1238	1239	1240	1241	1242	1243	1244	1245	1246	1247	1248	1249	1250	1251	1252	1253	1254	1255	1256	1257	1258	1259	1260	1261	1262	1263	1264	1265	1266	1267	1268	1269	1270	1271	1272	1273	1274	1275	1276	1277	1278	1279	1280	1281	1282	1283	1284	1285	1286	1287	1288	1289	1290	1291	1292	1293	1294	1295	1296	1297	1298	1299	1300	1301	1302	1303	1304	1305	1306	1307	1308	1309	1310	1311	1312	1313	1314	1315	1316	1317	1318	1319	1320	1321	1322	1323	1324	1325	1326	1327	1328	1329	1330	1331	1332	1333	1334	1335	1336	1337	1338	1339	1340	1341	1342	1343	1344	1345	1346	1347	1348	1349	1350	1351	1352	1353	1354	1355	1356	1357	1358	1359	1360

UNITED STATES PATENT OFFICE.

BIRGER A. CLEPP, OF MINNEAPOLIS, MINNESOTA.

MARK-UP TABLE.

1,305,062.

Specification of Letters Patent. Patented May 27, 1919.

Application filed April 19, 1918. Serial No. 229,532.

To all whom it may concern:

Be it known that I, BIRGER A. CLEPP, a citizen of the United States, resident of Minneapolis, county of Hennepin, State of Minnesota, have invented certain new and useful Improvements in Mark-Up Tables, of which the following is a specification.

In selling merchandise at retail, the merchant often wishes to know what the selling price should be in order that he may realize a certain per cent. over the cost price and the merchant sometimes wishes to know how much he can afford to pay for an article of merchandise to sell at a certain price and 15 realize a certain percentage or profit.

The object of my invention is to provide a table by means of which the merchant at a glance can determine what the retail price should be to make a certain percentage or 20 profit and can also ascertain what he can afford to pay for merchandise that sells at a certain price to obtain the desired percentage of profit thereon.

The invention consists generally in a mark 25 up table, all as hereinafter described and particularly pointed out in the claims.

In the accompanying drawings forming part of this specification,

Figure 1 represents a portion of a table 30 embodying my invention,

Fig. 2 is a similar view of a portion of a table designed particularly for a certain line of goods, such as suits and overcoats, where the line is smaller, and there is not such a 35 wide range of prices either in cost or the selling price.

In the drawing 2 represents a sheet divided horizontally by parallel lines 3 into a series of narrow spaces which are in turn 40 divided vertically by parallel lines 4 to form a series of rectangular spaces. The spaces at the left hand end of the sheet, which I will designate by reference numeral 5, and extending vertically of the sheet are used for 45 the figures representing the cost of the articles and there may be more or less vertical rows of these figures, according to the number of cost prices which the merchant may desire to appear therein. In this particular 50 illustration I have shown three of these vertical rows and they are preferably arranged in parallel relation, instead of one continuous row to economize in space and the size of the sheet. At the head of these columns I 55 preferably insert the words "Cost per dozen", indicating the price the merchant

paid per dozen for the articles on the sheet. At the upper edge of the sheet I provide a series of spaces 6 with horizontal rows of figures therein corresponding in number to 60 the cost columns and representing the retail prices, the words "Retail each" being preferably inserted in a blank space in the upper left hand corner of the sheet. In the spaces formed by the intersections of the vertical 65 and horizontal lines corresponding substantially in form and which I will designate by numeral 7, I place figures representing the percentage of profit of the retail price over the cost, and if the merchant having, for instance, neckwear costing \$4.25 per dozen wishes to know what his profit would be if he sells them at 50¢ each, will note the figures at the intersection of the lines forming the spaces in which the figures \$4.25 and 50¢ 70 appear, will find that the percentage of profit is 29 $\frac{2}{10}$ %. If he has shirts costing \$10.50 per dozen and wishes to make 30% profit, he will find that he must sell them for \$1.25 each, and so on down through the various articles on the table. 80

If the merchant desires to find the mark up on goods costing less than \$4.00, or the lowest figure in the cost column, he can divide any of the figures shown in the three 85 cost columns by ten and will thereby obtain additional cost figures, and the corresponding retail figures in the proper line must also be divided by ten. In other words, the mark up of the multiple of any cost shown in the 90 three vertical columns may be obtained, but the same corresponding multiple of the retail price in the corresponding line of retail prices must also be used.

Should the merchant wish to find the mark 95 up of any cost higher than the highest figure in the cost column, he will divide both the cost and the retail by two and then find the proper mark up in the regular way. If a still higher mark up and higher retail is desired, divide by a higher number, such as 3, to come within the scope of the table. 100

In buying merchandise, this table will be found extremely useful, as the merchant may be shown an article, such as a shirt, for 105 which he will know he cannot charge more than \$1.50 retail. The question arises in his mind, then, how much can he afford to pay for a shirt retailing for \$1.50 and be able to make a profit of approximately 35% with 110 discount? Turning to the sheet, and the figures \$1.50 in the retail row, follow down

the column to the figures 34.7%, the nearest to the profit he desires to make, then move toward the left across the sheet to the second cost column and the figures \$11.75 are found, 5 which represent the price the merchant can afford to pay for the shirts to sell at \$1.50 and make a profit of 34.7%. The same will be true of all the other articles on the sheet.

In Fig. 2 the same principle is applied to 10 a smaller line of goods, such as suits and overcoats, the cost price being shown in the vertical column 8 at the left hand end of the sheet and the selling price in the horizontal column 9 at the top and the percentage figures in the little squares 10 formed by the intersection of the vertical and horizontal lines.

In using this table, if the merchant bought 15 suits at \$11.00 and wishes to sell them at \$20.00, his percentage of profit would be 45%. This table does not show any figures of a quarter of a dollar and in order to find 20 these percentages the merchant will take the mean percentage of \$11.00 and \$11.59 for the \$11.25 cost and \$11.50 and \$12.00 for the \$11.75 cost. Suppose the merchant had 25 decided on a selling price of \$14.00 and wants to run as a special with a profit of say 26%, what should he pay for the suits? After 30 finding the figure "14" in the horizontal row at the top of the sheet, he will run down this column to the figures representing 25%, the nearest to his desired percentage of profit, and will then follow the horizontal row to 35 the left where, in the vertical column of cost prices, he will find the figures \$10.50, which represent the amount he can afford to pay for the suit which he wishes to sell at \$14.00 and realize a profit of approximately 26%.

40 In the same manner the proper cost price can be ascertained from the other desired retail prices on the sheet. It will be understood that the sheets are of any suitable size for convenient reference, only a portion of 45 the top of each sheet being shown herein. The principle, however, of ascertaining the cost or retail prices or percentages of profit is the same throughout all the figures on the sheet and consequently I have thought that 50 an illustration of a portion of each sheet would be sufficient.

Assuming that the merchant has a 25%

expense and he wants to make a 30% gross mark up, he will find that \$11.00 suits and overcoats should be marked to sell at \$16.00, 55 \$11.50 suits or overcoats at \$16.50 and so on. In this way the merchant is able to save a great deal of time in ascertaining the proper selling price with the desired basis of profit or what he can afford to pay for garments to 60 sell at a certain price and still earn the desired profit.

I claim as my invention:

1. A mark up table comprising a sheet 65 divided by vertical and horizontal lines to form a series of spaces, the spaces in a vertical column at one end of the sheet having the cost prices therein and the spaces in a horizontal row at a longitudinal edge of the sheet having the retail prices therein, and 70 the spaces on the sheet at the intersection of the horizontal and vertical columns having figures therein representing the percentage of profit of the selling price over the cost.

2. A mark up table comprising a sheet 75 having cost figures in a column at one edge of the sheet and retail figures in a row at right angles to the cost figures, the spaces on the sheet at the intersection of straight lines through said cost and retail figures having 80 figures representing the percentage of profit of the selling price over the cost, or the percentage which will be earned when goods sold at a certain retail price are bought at a certain cost.

3. A mark up table comprising a sheet divided by vertical and horizontal lines into 90 a series of spaces, a series of columns of cost figures being entered in said spaces at one end of the sheet and a corresponding number of rows of selling prices being entered in said spaces at one edge of the sheet, the spaces at the intersections of said vertical and horizontal rows having figures therein 95 representing percentages of profits whereby the merchant, knowing the cost price and the desired percentage of profit, can readily determine the retail price or knowing the desired retail price and percentage of profit, can ascertain what the cost should be.

In witness whereof, I have hereunto set my hand this 13th day of April, 1918.

BIRGER A. CLEPP.
